UNITED STATES PATENT OFFICE.

OSCAR HAMMERSTEIN, OF NEW YORK, N. Y., ASSIGNOR TO MALVINE HAMMERSTEIN, OF SAME PLACE.

CIGAR-MACHINE.

SPECIFICATION forming part of Letters Patent No. 272,958, dated February 27, 1883.

Application filed November 28, 1882. (No model.)

To all whom it may concern:

Be it known that I, OSCAR HAMMERSTEIN, of New York city, county and State of New York, have invented an Improvement in Machines for Making Cigars and Cigarettes, of which the following is a specification.

Figure 1 is a plan or top view of my improved machine for making cigars and cigarettes. Fig. 2 is a bottom view of the swiveled suction-plate thereof; Fig. 3, a vertical longitudinal section of the machine, the line *c c*, Fig. 1, indicating the plane of section; Fig. 4, a vertical transverse section taken on the plane of the line *k k*, Fig. 1.

15 This invention relates to improvements on machinery for holding the wrappers of cigars and cigarettes in place on the table before and at the time such wrappers are being applied as coverings to cigars and cigarettes; and it 20 consists in the employment of a hollow and movable table, which table has a perforated upper face, in connection with suction apparatus that communicates with the hollow space in said movable table.

25 The invention also consists in further details of improvement, that are hereinafter more fully specified.

The invention is an improvement on the patent, No. 261,849, granted to me August 1, 1882.

30 In the accompanying drawings, the letter *A* represents the suction-pipe, which is in communication with suitable apparatus for drawing air through it. From this pipe *A* project, at proper intervals, branches *B*, each of which

35 branches communicates with a table, *C*. A suitable valve, that can be raised or lowered at will by a treadle or otherwise, is contained in each branch *B*, as indicated at *a* in Fig. 3.

The table *C* is by preference of about the form 40 shown in Figs. 1 and 2—that is, more or less oval—and has its upper face constructed of a sheet-metal plate, *b*, (although other material may be employed,) through which plate are drilled series of small openings, that are indicated at *d*.

45 Below this perforated portion *d* the table *C* is hollow, having an elongated space, *e*, that is clearly shown in Figs. 3 and 4, and in this space there is, by preference, a vertical rib or ribs, *f*, for the support of 50 of the perforated portion of the plate *b*, to prevent it sagging down under the influence of

suction. The upper end of each branch pipe *B* passes through a stationary platform, *D*, and extends somewhat above said platform, as shown in Fig. 3, and this portion of the pipe *B* which extends above the platform *D* enters a circular hole in the bottom of the table *C*, and communicates with the space *e* that is in said table, all as clearly indicated in Fig. 3. The table *C* rests on the platform *D*. The attendant can place the wrapper for a cigar or cigarette upon the perforated part of the table *C*, and opening the valve *a*, the suction will cause this wrapper to be held tightly to the surface of the table *C*. The bunch or filling 65 part of the cigar or cigarette can then be placed upon one end of the wrapper, and being rolled along, the wrapper will be caused to be wound upon it in proper manner, the suction meanwhile holding so much of the wrapper as is not 70 yet wound around the bunch flat upon the table. While operating, the attendant can turn the table around the end of the pipe *B*, so as to always have the bunch properly before him, thus making it unnecessary for the attendant to partly walk around the table in laying 75 the wrapper around the bunch of tobacco.

Instead of placing the table *C* around the projecting end of the pipe *B*, as shown in Fig. 3, any other manner of swiveling the table *C* 80 to said pipe *B*, and at the same time allowing communication between the space *e* of the table and the pipe *B*, may be substituted without departing from the spirit of my invention.

I claim—

1. The swiveled table *C*, having perforated top plate, and space *e* below said top plate, combined with the pipe *B*, which communicates with said space *e*, and constitutes the center around which the table can be turned, 90 substantially as described.

2. The table *C*, having perforated top plate, *b*, and space *e* below said top plate, in combination with the rib *f*, substantially as and for the purpose described. 95

This specification of my invention signed by me this 27th day of November, 1882.

OSCAR HAMMERSTEIN.
